Specification for Design.

Patented July 27, 1915.

Application filed May 8, 1915. Serial No. 26,915. Term of patent 14 years.

To all whom it may concern:

Be it known that I, JOHN F. CARVER, a citizen of the United States, residing at Boston, in the county of Suffolk and State of Massachusetts, have invented a new and original and ornamental Design for Bottles, of which the following is a specification, reference being had to the accompanying drawings, forming a part thereof.

In the drawings, Figure 1 is a plan view, Fig. 2 is a front view and Fig. 3 a side elevation of a bottle showing my new design.

I claim—

The ornamental design for a bottle as shown.

JOHN F. CARVER.
